UNITED STATES PATENT OFFICE.

FRANK U. LONG AND MORTIMER L. PACKER, OF COLUMBUS, OHIO, ASSIGNEES TO THE
OHIO STATE STOVE COMPANY, OF COLUMBUS, OHIO, A CORPORATION OF OHIO.

DESIGN FOR A GAS-STOVE.

40,368.

Specification for Design.

Patented Nov. 23, 1909.

Application filed July 1, 1909. Serial No. 505,525. Term of patent 7 years.

To all whom it may concern:

Be it known that we, FRANK U. LONG and MORTIMER L. PACKER, citizens of the United States, residing at Columbus, in the county of Franklin and State of Ohio, have invented a new, original, and ornamental Design for Gas-Stoves, of which the following is a specification, reference being had to the accompanying drawing, forming part thereof.

The figure is a front elevation of a gas stove, showing our new design.

We claim:

The ornamental design for a gas stove, as shown.

FRANK U. LONG.
MORTIMER L. PACKER.
